FOREIGN PATENT DOCUMENTS

EP	1759819	11/2008
WO	WO2004113033	12/2004

Primary Examiner — Ricky Pham(74) *Attorney, Agent, or Firm* — Thompson Coburn LLP;
Matthew Himich(57) **CLAIM**

The ornamental design for a food processing apparatus, as shown and described.

DESCRIPTION

FIG. 1 is a front, right side perspective of the food processing apparatus showing my new design;

FIG. 2 is a right side elevational view thereof;

FIG. 3 is a left side elevational view thereof;

FIG. 4 is a rear elevational view thereof;

FIG. 5 is a front elevational view thereof;

FIG. 6 is a top plan view thereof; and,

FIG. 7 is a bottom plan view thereof.

The broken lines in FIGS. 1-7 of the food processing apparatus is for the purpose of illustrating environment, and forms no part of the claimed design.

1 Claim, 7 Drawing Sheets(56)
